US0D1037650S

(12) **United States Design Patent** (10) Patent No.: **US D1,037,650 S**
(45) Date of Patent: ** Aug. 6, 2024

(54) **BACKPACK**

(71) Applicant: **DECATHLON**, Villeneuve d'Ascq (FR)

(72) Inventor: **Clément Parel**, Villeneuve d'Ascq (FR)

(73) Assignee: **DECATHLON**, Villeneuve d'Ascq (FR)

(**) Term: **15 Years**

(21) Appl. No.: **29/891,943**

(22) Filed: **May 11, 2023**

Related U.S. Application Data

(62) Division of application No. 29/776,654, filed on Mar. 31, 2021, now Pat. No. Des. 990,870.
